UNITED STATES PATENT OFFICE.

MAX J. GEEL, OF VIENNA, AUSTRIA-HUNGARY, ASSIGNOR TO MERGENTHALER LINOTYPE COMPANY, A CORPORATION OF NEW YORK.

TYPOGRAPHICAL COMPOSING-MACHINE.

1,136,521.

Specification of Letters Patent. Patented Apr. 20, 1915.

Application filed January 23, 1915. Serial No. 4,072.

To all whom it may concern:

Be it known that I, MAX J. GEEL, a citizen of the Swiss Republic, residing at Theobaldgasse 17, Vienna, VI, Austria-Hungary, have 5 invented new and useful Improvements in Typographical Composing-Machines, of which the following is a specification.

This invention relates to typographical composing machines, such as those known 10 commercially under the trade-mark "Linotype," and particularly to those equipped with a plurality of magazines respectively containing matrices or type-dies (which latter are to be understood as included in the 15 term "matrices" as hereinafter employed), of different fonts or faces, any one of which magazines may be brought into operative position, and with a single distributing mechanism arranged to deliver matrices into 20 the magazine which for the time being is in operative position. In such machines, it is essential that all the matrices which have been composed from one magazine be returned thereto by the distributing mecha- 25 nism, before any change of magazine is effected, as any such premature change will result in the matrices being distributed into a wrong magazine. The operator, therefore, must be particularly careful in this respect. 30 He has generally relied upon the cessation of the sound of the falling matrices into the magazines to indicate when it is safe to effect a change of magazine, but this method has proved unsatisfactory, especially in 35 rooms where the noise of other machinery renders hearing uncertain. The difficulty is removed, according to the present invention, by providing a visible signal which will definitely indicate to the operator whether 40 or not matrices are present in the distributing mechanism.

The invention will be described with reference to the accompanying drawing, which shows diagrammatically a constructional 45 form thereof.

The distributer bar 1, which is of known construction, is, according to the present invention, electrically insulated from the machine frame, and is connected to one, say the 50 positive, pole of an electric battery or other electric-current generator 2, the opposite pole of which is in connection with one terminal 3 of a lamp 4. The second terminal, 5, of this lamp is electrically connected to a 55 convenient part of the machine frame. It

will be seen that, as the distributer bar 1 is insulated from the machine frame, the connections just described form an incomplete electrical circuit, which would be closed, and effect the lighting of the lamp 4, by establishing a path for the current between the machine frame and the distributer bar 1. Now a matrix 6, during the known process of distribution, is brought into engagement with the distributer bar 1, and is propelled 65 along that bar by engaging with the known distributer screws 8, which engage its lugs 7 and which are mounted in the machine frame. Consequently, so long as a matrix 6 is hanging from the distributer bar 1, an 70 electrical connection between the said bar and the machine frame, is established, through the matrix and the distributer screws, and the lamp 4 will be lighted. The dropping of the last matrix from the bar 75 will open the circuit and extinguish the light. The lamp can be placed in a position where it can be readily seen by the operator, who will thus be provided with a reliable indication of the presence of a matrix in the 80 distributer, and will know, by the absence of the light, when a change of magazine may be safely effected.

Obviously, without departing from the scope of the invention, any form of electrically-operated visual indicator may be substituted for the lamp, and the arrangement of the circuit may be modified in any convenient manner, provided that it is adapted to be closed by a matrix in the dis- 85 tributer.

Having thus described my invention what I claim and desire to secure by Letters Patent of the United States is as follows:—

1. In a typographical composing machine, 95 the combination of a distributing mechanism for the type or matrices, and an electrically operated signal controlled automatically by the type or matrices undergoing distribution.

2. In a typographical composing machine, 100 the combination with a distributing mechanism of electric-current conductors forming a normally open circuit adapted to be closed by a matrix passing through the distributing mechanism, and an indicator in the said circuit operated when such closure is effected.

3. In a typographical composing machine, 105 the combination of an electric-current generator, a distributer bar insulated from the

machine frame and connected with one pole
of the said generator, distributer screws in
electrical connection with the machine
frame, and an electric lamp having its two
5 terminals respectively connected to the ma-
chine frame and the second pole of the said
generator.

In witness whereof I have hereunto set my
hand in the presence of two witnesses.

MAX J. GEEL.
